UNITED STATES PATENT OFFICE.

GEORGE MARSHALL CLARK, OF HIGGANUM, CONNECTICUT.

THRUST-BEARING JOURNAL-BOX.

SPECIFICATION forming part of Letters Patent No. 356,099, dated January 18, 1887.

Application filed September 3, 1886. Serial No. 212,613. (No model.)

To all whom it may concern:

Be it known that I, GEORGE MARSHALL CLARK, of Higganum, (in the town of Haddam,) county of Middlesex, and State of Connecticut, have invented certain new and useful Improvements in Thrust-Bearing Journal-Boxes; and I do hereby declare that the following specification, taken in connection with the drawings furnished and forming a part thereof, is a clear, true, and complete description of the several features of my invention.

The object of my invention is to provide a simple and effective thrust-bearing journal-box, by which all variations in the lines of thrusting force to which such bearings are or may be subjected will be equally resisted or borne, and with a minimum of friction, and also with a minimum liability of uneven wear at any of the contact-surfaces.

A thrust-bearing box embodying my invention is of special value in connection with shafts inclined to each other and rotated at various angles under conditions which necessarily involve thrusting force toward each other; but it has also substantial value in connection with step-seats, and also with knuckle-joint levers adapted to heavy service.

After fully describing my improved thrust-bearing boxes of various kinds illustrated in the drawings, the features deemed novel will be specified in the several clauses of claim hereunto annexed.

Referring to the drawings, Figures 1, 2, and 3 illustrate, respectively, in top, bottom, and side views, a double thrust-bearing box constructed in accordance with my invention, as when adapted for use with two revolving thrust-shafts. Fig. 4 is a lateral vertical central section of the same. Fig. 5 illustrates, in vertical section, a simple form of thrust-bearing box adapted to service as a step-bearing. Fig. 6 illustrates, in vertical section, a double thrust-bearing box adapted for use with knuckle-joint levers.

Referring to Figs. 1, 2, 3, and 4, it is to be understood that the hanger A may be indefinitely varied in form and construction without departure from my invention. As here shown, it is adapted to slide into and interlock with a grooved hanger plate or socket, (not shown,) and which in turn would be secured to any suitable foundation, whether upright or hori-

zontal. The shell of the journal-box B is constructed in two parts, *a* and *b*, the part *a* being integral with the hanger and the part *b* bolted thereto on a line coincident with the center of the interior of the box. The chamber *c* within the box is spherical, and contains the ball *d*, which is composed of metal, or an alloy of any suitable kind, according to the character of service to be performed. If specially exposed to corrosive influences and to heavy service, phosphor-bronze may be employed to good advantage; but in most cases steel or iron can be relied upon, and I have obtained good results with cast-iron balls in certain lines of service. In its best form said ball is hollow and provided with a number of perforations, as at *d'*, thus affording a lubricating-chamber, into which from time to time a solid lubricant may be packed for emergencies, as when regular oiling has been neglected and the bearing heated, whereupon the reserve lubricant will be delivered. At each side of the box there is an annular opening, *a'*, for the reception of a cup-shaped thrust-bearing, *e*, having a concave face at *e'*, conforming to the surface of the ball *d*, and also an exterior convex face, *e''*, corresponding to the coincident interior surface of the box-chamber, and at *e'''* an annular neck much smaller than said opening *a'*. At the outer end of said cup-shaped thrust-bearing there is in this instance a flange, *e'*, which can with bolts serve as a means for coupling it to a revolving shaft, although in this instance the shafts *f* have each a threaded neck which occupies a tapped central hole in said flange, which extends through the neck. It is, however, to be understood that it is immaterial how said shafts may be coupled to the cup-shaped bearings *e*, and that said shafts and said bearings may be integral without in any manner affecting my invention. In this form of thrust-box it will be seen that when either or both of said shafts are revolved under equal thrusting strains toward each other each shaft will serve as an abutment for the other, and that the interposed ball will be free to revolve with either and independently of the other, or with both, and that fresh contact-surfaces will be continuously presented, thus maintaining uniform bearing-contacts with a minimum liability of unequal wear. It

will also be seen that if either shaft be subjected to thrusting strains in excess of those borne by the other the box itself resists said unequal strain at its bearing-contact with the 5 convex or outer face of the thrust-bearing *e* of the shaft by which the lesser thrusting force is borne, said convex face being interposed between the ball and the coincident surface of said box.

10 Now, referring to Fig. 5, it is to be understood that the vertical shaft *g* revolves, as, for instance, with a turbine water-wheel thereon, and hence it must have a step-bearing capable of sustaining the vertical thrust incident to the 15 weight of the shaft and its wheel, and, as in some grinding-mills, the weight also of a millstone. In this form of bearing the shaft *g* has a concave or cup-shaped thrust-bearing, *e*, and a ball, *d*, as before described; but the 20 journal-box shell *h* differs from the double box before described in having a cup-shaped or concave seat at *h'* for directly receiving the ball, and said shell is constructed in two parts bolted together, for properly locking the ball- 25 and-shaft seat therein as against any undue freedom of movement. With this form of thrust-bearing it will be readily seen that should the box, by the uneven settling of its foundation in any direction of inclination, be 30 itself thrown out of its normal position with relation to the shaft, the relations of the contacts at the upper and the lower surfaces of the ball would remain substantially the same, and that a minimum of friction would be involved without laterally straining the vertical 35 shaft.

In Fig. 6 the thrust-bearing box *i* is applied in connection with the levers *i'*, coupled to form the well-known "knuckle-joint," sometimes 40 called "toggle-joint." In this case the levers *i'* have no rotative movement on their longitudinal axes, but each being provided with a concave thrust-bearing, *e*, and both of these engaging with the interposed ball *d*, it will be 45 seen that contacts are afforded which induce more or less rotation of the ball, and that downward strains on the box *i* induce equal thrusting strains on both levers, and that the ball and the concave seats bear said strains 50 substantially as when rotative thrust-shafts are used, as shown in Figs. 1 and 5.

However the form of my box may be varied, or whatever the special use intended, it must contain a ball interposed between two cup-shaped or concave seats, whether both of the latter be movable independently of the ball and the shell of the box, or whether only one of said seats is thus movable and the other stationary.

My thrust-bearing box differs radically from 60 the well-known ball-and-socket joint in many respects, although in both a corresponding degree of freedom of angular movement is afforded. In the ordinary ball-and-socket joint, however, the contacts are comparatively 65 fixed in their relations to each other, whereas in my boxes said contacts are constantly variable, and hence no unequal wear can occur, whereas in the ball-and-socket joint wear 70 unduly results at those contacts which are substantially at right angles to the line in which thrusting force is applied to the joint.

Many other forms of my boxes could have been shown, but those illustrated fairly indicate three general varieties, and they will no 75 doubt be ample for guiding persons skilled in such matters to the production of other forms which may be deemed better suited to some special uses. So, also, might I have indicated many other connections in which my thrust- 80 boxes can be profitably employed; but I deem it only necessary to add that I have found the form shown in Fig. 1 to be of great practical value for coupling the shafts of disk-harrows; and also that the form indicated in Fig. 5 is 85 admirably suited for the steps of heavy spindles in large screw-stem valves intended to be opened against heavy pressures.

Having thus described my invention, I claim as new and desire to secure by Letters Patent— 90

1. The combination, substantially as hereinbefore described, of a ball, a journal-box inclosing said ball, a cup-shaped bearing-seat within said box, and a cup-shaped thrust-bearing which is fitted to said ball, whereby, regardless of variations in the direction of thrusting force, said ball will afford shifting contacts to both of said cup-shaped seats. 95

2. The combination, substantially as hereinbefore described, of a journal-box, a pair of revolving shafts each provided with a cup-shaped seat and occupying portions of said box, and a ball interposed between said shaft-seats and within said box, whereby thrusting strains upon said shafts, or either of them, toward said box is borne by said ball, and the contact-surfaces of said ball constantly shifted. 100

3. The combination, with a journal-box, of a pair of interior concave or cup-shaped seats and an interposed hollow perforated ball, substantially as described, whereby said ball may be charged with a lubricant for gradual delivery. 110
